UNITED STATES PATENT OFFICE.

ANDREW J. McCREADY, OF PARKSLEY, VIRGINIA.

VINE-CUTTER.

No. 815,203.

Specification of Letters Patent.

Patented March 13, 1906.

Application filed December 19, 1905. Serial No. 292,457.

To all whom it may concern:

Be it known that I, ANDREW J. McCREADY, a citizen of the United States, residing at Parksley, in the county of Accomac and State 5 of Virginia, have invented certain new and useful Improvements in Vine-Cutters, of which the following is a specification.

This invention relates to improvements in vine-cutters of that class which are drawn by 10 horses and used for cutting vines that grow close along the ground, such as potato and pea vines.

The improvements are particularly applicable to such vine-cutters as the one for 15 which Letters Patent of the United States were granted to me November 13, 1900, No. 661,811.

The invention is illustrated in the drawings herewith, in which—

20 Figure 1 is a side view of the improved vine-cutter. Fig. 2 is a detail view taken on section 2 2 through the beam, showing the runner parts arranged for a single runner. Fig. 3 is a detail showing the runner parts arranged for a double runner. Fig. 4 is a detail of the rear standard of the runner. Fig. 5 is 25 a sectional view, on a larger scale, on line 5 5 of the beam, showing details of the improved adjustable bearings of the cutting-blades. Fig. 6 is a side view of the point, cutter-blade, and the adjusting-brace. Fig. 7 is an edge view, on a larger scale, of the parts shown in 30 Fig. 6.

In the drawings the letter A designates the 35 beam, which has two slots c c' opening vertically through it. An improved runner is provided, comprising two bars d, both curved at their forward end like a sled-runner. These two bars may be arranged with their sides in 40 close contact, as in Fig. 2, to form a single runner, or they may be separated and spaced apart, as in Fig. 3, to form a double runner. The extreme forward and upward curved end of each runner has a lateral arm d', which 45 carries a bolt d'.

The forward ends of the two runner-bars are held by a vertically-adjustable head e, comprising an inverted-T piece the shank or main member of which is inserted in the for- 50 ward slot c in the beam from its under side and is held by a pin or bolt f, and the cross-head member has position below the said beam. A slot e' is in each end of the cross-head. It will be seen that the two lateral 55 arms d' on the runners take below the cross-head, and the bolt d', carried by each lateral

arm, projects through one of the slots e' in the cross-head. The nut on the bolt enables the latter to be tightened, and thereby the parts secured in position. It will also be seen 60 that the two runner-bars d may be set, as in Fig. 2, with their lateral arms d' pointing away from each other, in which case they will form a single runner, or they may be set, as in Fig. 3, with the lateral arms d' pointing 65 toward each other and forming a double runner.

The rear part of the runner is held by an inverted-T piece similar to that used at the forward end and the shank of which is inserted 70 in the rear slot c'. Fig. 4 shows the construction of these rear parts; but the beam is omitted in this figure. Two rear supporting-standards u are employed, one for each runner. Each standard has its lower end secured 75 to one of the runners by a bolt or rivet v, and the upper end of each has a lateral arm u', provided with a slot u² and carrying a bolt u³. It will be understood that the lateral arms u' on the rear standards take below the cross- 80 head and are secured by the bolts u³ and may be adjusted by the slots.

When the runner is arranged to act as a single runner, the rear parts will have the position shown in full lines in Fig. 4; but when 85 arranged to act as a double runner—that is, the two runner-bars separated and spaced apart—the rear supporting-standards u will have the position indicated by the broken lines in Fig. 4.

The foregoing-described construction provides for using the cutter with either a single or double runner, according to the topography or character of the land.

The cutter-blades C are each carried by a 95 U-shaped arm B, one round end prong i of which fits in a bearing g, whereby the other arm l, to which the blade is attached, may be adjusted in a swinging or curved plane, caused by said round end being turned in the bearing. A set-screw i' on the said bearing 100 g is used to retain the prong in any position of adjustment. The means of adjustment just described is shown in my prior patent already named.

I have now provided additional means for effecting another adjustment—namely, in the present case the bearing g itself is made adjustable by being mounted on a trunnion g', so that said bearing may be tilted or inclined in a plane at right angles with respect 110 to the aforesaid swinging or curved plane.

The bearing g , therefore, in this improvement is not rigidly secured to the side of the beam A, as in my prior patent. In the present instance this bearing has a boss on its upper side and a bore or hole g^2 opens through this boss in a direction at right angles relatively to the bore or bearing in which the round end of the prong i fits. The said bore g^2 takes on the trunnion g' , which projects horizontally from the side of the beam A. Thus the bearing g may be tilted on the trunnion in a vertical plane at right angles with respect to the swinging or curved plane in which the free end of the U-shaped arm B may move.

15 The trunnion g' in the present instance is fixed to a plate p , securely bolted to the side of the beam. A plate of this kind with a trunnion is secured at each side of the beam A, as seen in Fig. 5. A set-screw q enters through the boss into the side of the bore or hole g^2 and impinges against the trunnion g' , and thereby retains the bearing g from movement and holds it at any angle to which it may be tilted.

25 I have improved the construction of the cutter-blade parts and have provided means that enable the cutter-blade to be adjusted independently of the point and also independently of the U-shaped arm B that carries the blade and point. This construction will now be described.

The end of the arm l fits in a socket r and is held there by a set-screw s . The letter t designates the point, C the cutter-blade, and w the adjusting-brace. The point t is connected with the socket-piece r by a pivot-screw r' on the runner part of the point, and the latter has a short crosswise slot in which takes a set-screw t' . By this construction 35 the said point may be tilted more or less on the pivot-screw r' independent of the socket-piece and held by the set-screw t' . The point t has an upper front pivot t^2 , to which the forward end of the cutter-blade C is jointed. 40 The point t also has a rear pivot t^3 , to which the adjusting-brace w is attached. This brace is a connection between the point-piece t and the cutter-blade C and serves to stay and support the blade in any particular adjustment on the front joint t^2 to which it may be set. The brace w is movable on the rear pivot t^3 . This brace has a bend or angle part w' , which is provided with a slot x , and a set screw or bolt x' , attached to and carried 45 by the blade C, projects through said slot and may be tightened when the parts have the desired position. The brace w at its end has

another slot y , through which projects a set-screw y' , which is also attached to and carried by the blade C. The two slots x and y in the brace are shaped to permit the brace to move on its pivot t^3 with due regard to the fact that the radius from the said pivot to the slot x is shorter than the radius on the cutter-blade from the pivot t^2 to the bolt x' , 50 which is movable in said slot x . The arrangement here shown of point-piece t , cutter-blade C, and brace w enables the cutter-blade to be adjusted independently of said point-piece and also independently of the end 55 of the U-shaped arm.

It will be seen that the point-piece t may be tilted relative to the socket-piece r and that the heel end of the cutter-blade may be raised or lowered relative to the point-piece. 75

Having thus described my invention, what I claim as new, and desire to secure by Letters Patent, is—

1. In a vine-cutter, the combination of a beam; a runner composed of two bars which 80 are adjustable for use for both a single runner and a double runner; carrier-arms attached to the beam at each side, and a cutting-blade carried by each of said arms.

2. In a vine-cutter the combination of a beam; a runner; a bearing, g , mounted on a trunnion projecting from the side of the beam; and a blade-carrier arm having a rounded upper end which fits in said bearing, whereby the free end of the arm may be adjusted in a swinging or curved plane, and the bearing of the arm may be adjusted by tilting in a plane at right angles with respect to the said curved plane. 85

3. In a vine-cutter, the combination of a beam; a runner; a U-shaped arm pivoted by one of its prongs to the beam; a vine-cutter blade and point-piece carried by the other prong, and said blade and point-piece each adjustable independently of the said prong. 90

4. In a vine-cutter, the combination of a beam; a runner; a U-shaped arm pivoted by one of its prongs to the beam; a point-piece carried by the other prong of said arm; a cutter-blade jointed to the point-piece and an adjusting-brace also jointed to the point-piece and set-screws for securing said brace to the cutter-blade. 100

In testimony whereof I affix my signature in presence of two witnesses.

ANDREW J. McCREADY.
